APPARATUS FOR VENTING HEAT TRANSFER UNITS OF A STEAM-HEATED DRYING SYSTEM OR THE LIKE

Charles J. Lahman, Dayton, Ohio

Application May 19, 1948, Serial No. 27,976

3 Claims. (Cl. 34—119)

1

This invention relates to an apparatus for venting heat transfer units of a steam heated drying system or the like.

A common type of drier used in connection with paper making machines, and for other purposes, comprises a series of steam heated heat exchange units, such as rotating drums, about which the paper or other material to be dried passes successively. The steam is introduced into each unit through an axial passage and the condensate is withdrawn from the unit through an eduction pipe extending through the steam supply passage. In the operation of such a drier or during the intervals when it is not in operation air and non-condensable gases or vapors enter the units and adversely affect the drying operation. For example when the drier is shut down, and the steam supply cut off, the cooling of the system condenses the steam remaining in the system and creates therein a partial vacuum, or a pressure lower than atmospheric pressure, and air is drawn into the system through any leaks which may exist therein. Steam entering the units from the boiler may carry with it vapors or gases which are non-condensable under the conditions existing in the units. Such air and non-condensable gases or vapors reduce the transfer of heat from the unit to the material being dried, as by reducing the temperature in the units and by forming an insulating film between the steam and the heat transfer surfaces of the units. The air and non-condensable gases and vapors entering the units are withdrawn therefrom through the eduction pipes and are carried with the condensate to a header with which the several units are connected and from which the condensate is returned to the boiler. When the condensate discharged from the units moves rapidly through the header the pressure of the latter is reduced below the pressure in the units and the heat units contained in the condensate in excess of the temperature corresponding to this lower pressure are released in the form of "flash" steam which, having a lower specific gravity than the condensate, tends to accumulate at the high point in the return line and to choke or otherwise obstruct the flow of condensate through the return line. Likewise air and non-condensable vapors and gases entering the header with the condensate, being of lower specific gravity than the condensate, tend to accumulate at the high point in the return line and to obstruct the latter.

One object of the invention is to provide a steam heated heat transfer system with means for continuously removing air and other non-

2

condensable gases or vapors from the unit or units of the system without obstructing or otherwise disturbing the continuous and rapid discharge of condensate from said unit or units, thus permitting the maximum transfer of heat from said unit or units to material in contact therewith.

A further object of the invention is to provide such a system with means for preventing air or other non-condensable gases or vapors which have been removed from a heat transfer unit or units, or steam flashed from the discharged condensate, from accumulating at a high point in the condensate return line and obstructing the flow of condensate therethrough.

A further object of the invention is to provide such a system in which the removal of air, gases, vapors and flash steam will be automatically controlled.

A further object of the invention is to provide such a system in which the air, gases, vapors and condensate are removed in such a manner as to provide equal distribution of the steam to the several units and to prevent "short circuiting" one or more portions of the system.

In the accompanying drawings Fig. 1 is a schematic side elevation, partly broken away, of a drying apparatus embodying the invention; Fig. 2 is a horizontal sectional view taken through the rotary joint between the steam supply pipe and the drum; and Fig. 3 is a sectional view, partly in elevation, of a temperature controlled relief valve.

In these drawings I have illustrated one embodiment of my invention and have shown the same as applied to a web drying apparatus of the type which comprises a series of rotatable heat transfer units or drums, but it is to be understood that the invention may take various forms and may be applied to heat transfer units of various kinds, used either for drying materials or for other purposes, and the word "drum" as hereinafter used is intended to include any heat transfer unit to which the invention may be applied.

The drying apparatus in which the invention is here embodied is of a well known type and comprises a series of rotatable drums 5 of which there is usually a relatively large number, three drums only being shown for the purpose of illustration. The several drums are mounted for rotation about parallel axes and are so arranged that a web of material may pass successively about the several drums in contact with a relatively large part of the outer or heat transfer surface of each drum. The drums may be sup-

ported and rotated in the conventional manner or in any other suitable manner and these features are not illustrated except that Fig. 2 shows the trunnion and bearing for one end of one of the drums. Each drum is separately connected with a source of steam supply, and in the arrangement shown a steam supply pipe 6 is connected at one end with a steam inlet at the axis of the drum and at its other end with a steam supply manifold or header 7, each steam supply pipe being provided with a cutoff valve 8. The header 7 may be connected with any suitable source of steam supply and in the present instance it is connected by a pipe 9 with a boiler 10, the pipe 9 being provided with a cutoff valve 11 and a pressure reducing valve 12. The manifold itself is provided adjacent the reducing valve with a safety valve 13 and a pressure gauge 14.

Portions of the steam introduced into the drums to heat the same will condense and the condensate must be removed from the drums. Further, as above explained, more or less air will frequently enter the drums and non-condensable gases and vapors will find their way into the drums, and these also must be removed. For this purpose each drum is provided with an eduction pipe 15 which, by siphoning or otherwise, withdraws both the condensate and the gaseous substances from the drum. Heretofore both the condensate and the gaseous substances have been delivered from the eduction pipe through a discharge conduit 16 to a condensate manifold or header 17, from which the condensate is returned to the boiler, as by a pumping type steam trap 18 connected by a conduit 19 with a combined water heater and tank 20, the tank being connected by a pipe 21 with a feed water pump 22 which delivers the heated water through a pipe 23 to the boiler.

The steam supply pipe and the eduction pipe may be of any suitable character and may be connected with the drum in any suitable manner. Usually the connection is made through a rotary joint such as is shown in Fig. 2. As there shown the steam inlet for the drum comprises a tubular element, or nipple, 24 rigidly connected with the drum at the axis thereof for rotation with the drum and communicating with the interior thereof. In the arrangement shown the tubular member has the inner end thereof screw threaded into an opening in the outer end wall of a hollow trunnion 25 by which one end of the drum is supported in its bearing 26. Mounted about the open outer end of this tubular member is a housing 27 which may be supported and held against rotation in any suitable manner. The tubular member extends through a relatively large opening 28 in the inner end wall of the housing, that is the end wall adjacent the trunnion, and is freely rotatable therein. Within the housing the tubular member is provided with an abutment 29 having a convex surface 30 which bears against a concave surface on an annular sealing member 31 extending about the tubular member 24 between the abutment and the end wall of the housing. A second abutment 32 is slidably mounted on the outer end portion of the tubular member and is also provided with a convex surface 33 engaging a concave surface on a second annular sealing member 34. The sealing members may be of any suitable heat resisting bearing material, such as graphite. A spring 35 confined between the abutments 29 and 32 presses the two abutments against the respective sealing members and thus tightly seals the joint. The outer end of the housing is closed

by a removable head 36 which is spaced a short distance beyond the end of the tubular member and against which the sealing member 34 bears. This end wall is provided with an extension 31 which projects outwardly beyond the body of the housing and has therein a passage 38 connecting the steam supply pipe 6 with the interior of the housing and, therefore, with the interior of the drum 5. The eduction pipe 15 comprises a second tubular member which extends through the tubular member 24 and is of an exterior diameter substantially less than the interior diameter of the tubular member 24, so as to provide a passage for the free flow of the steam from the supply pipe to the drum. The eduction pipe, or tubular member, 15 extends through the hollow trunnion 25 and then downwardly, as shown at 25a, to a point near the bottom of the drum, with which it is in open communication. The outer end of the eduction pipe extends beyond the outer end of the tubular steam inlet 24 and is mounted in and supported by the head 36 of the housing. The extension 31 of the housing is provided with a second passage 39 with which the eduction pipe is in open communication and which is connected with and in open communication with a short pipe 40 forming a part of the condensate discharge line. When, as has been heretofore customary, the condensate and gaseous substances withdrawn from the drum are all delivered through the condensate discharge conduit to the condensate header 17, the gaseous substances, having a lower specific gravity than the condensate, will separate therefrom and tend to accumulate at a high point in the discharge system and to obstruct the flow of condensate through the system, and this obstruction may be sufficient to completely block the flow of condensate from one or more of the drums. The main purpose of the present invention is to separate the gaseous substances from the condensate before the latter is delivered to the condensate header. To this end the connection between the main portion of the condensate discharge line 16 and the pipe 40 is in the nature of a two way coupling, one outlet of which is connected with the condensate discharge line and the other outlet of which is connected with a second conduit 41 and so arranged that the gaseous substances will separate from the condensate and rise through the conduit 41, while the condensate flows by gravity to the header 17. In the present instance the short pipe 40 is in a substantially horizontal position and the coupling is in the nature of a vertical T-coupling. The condensate discharge conduit 16 is directly connected with the lower end of the coupling and the second conduit, 41, is directly connected with the upper end of the coupling. The discharge conduit 41 for the gaseous substances of each drum is connected with an air and vapor manifold or header 42. It will be understood that more or less steam will be withdrawn from the drum along with the air and vapors and for the purpose of limiting the escape of steam from the drum each conduit 41 is provided with a restricted orifice 43. This orifice not only restricts the flow of steam but it also restricts the flow of other gaseous substances and thus prevents an excessive flow of steam, air or vapors from any one drum, which would tend to obstruct the air and vapor header and might so restrict the flow through the header as to isolate or short circuit one or more of the drums.

The illustrated apparatus usually operates at a steam drying pressure above eleven pounds, gauge, and at such pressure the air and non-con-

densible vapors entering the header are of a lower specific gravity than the steam and flash steam. Therefore the air and vapor header 42 is slightly inclined, that end thereof adjacent the boiler being the higher, so that the air and non-condensable vapors entering the same will accumulate at the higher end of the header, and must be from time to time withdrawn. For this purpose, I have provided an automatic temperature controlled relief valve which is so arranged that when the temperature in the higher end of the header falls below a predetermined temperature, due to the accumulation of air and vapor therein, the valve will open to vent the header, thus permitting the air and vapor to escape, and as the air and vapor escapes steam moves into the upper end portion of the header and restores the desired high temperature, and upon such restoration the relief valve is again closed. The relief valve may be of any suitable character which can be controlled in the manner stated. As here shown it comprises a valve casing 44 the end 45 of which constitutes the inlet and is connected by a pipe 46 with the higher end of the header 42, the latter being provided with a dome 47 with which the pipe 46 is connected. The other end of the valve casing is in open communication with the atmosphere. The flow of fluid through the valve is controlled by a spring seated valve member 48 the stem of which extends upwardly into a cylinder 49 where it is connected with a piston 50. The cylinder 49, above the piston, is connected with the intake side of the valve by a conduit comprising a part 51 and a part 52, the connection between the two parts being normally closed by a valve 53. The stem of the valve 53 bears against a diaphragm 54 and a plunger 55 is urged by a spring 56 in a direction to depress the diaphragm 54 and thus open the valve 53 and permit air to flow from the intake side of the valve casing to the cylinder 49 and thus open the valve and vent the header. The plunger 55 is held normally against movement by the spring 56 by a lever 57, the outer end of which is connected by a rod 58 with a plunger 59 which engages the lower side of a diaphragm 60 in a diaphragm chamber 61. The chamber 61 above the diaphragm is connected by a flexible conduit 62 with a thermostat tube 63 containing an expansible fluid. The expansion of the fluid in the thermostat exerts a downward pressure on the diaphragm 60 which resists the upward pressure of a spring 64 acting on the plunger 59. The pressure so exerted on the diaphragm by the thermostat is such as to prevent the upward movement of the plunger 59 so long as the temperature to which the thermostat is subjected is at or above a predetermined temperature. When that temperature falls below the predetermined temperature the pressure on the diaphragm is reduced and the spring 64 is permitted to move the plunger 59 upwardly and thus release the lever 57 and the plunger 55 for movement by the spring 56 and thereby cause the operation of the valve member 48 to open the valve. When, as shown in Fig. 1, the thermostat tube 63 is inserted in the higher end of the header 42 a fall in the reduction of temperature in the latter will result in the opening of the relief valve to permit the escape of air and as the air escapes steam moves into contact with the thermostat tube and the valve is again closed. The diaphragm spring 64 is adjustable to vary the pressure at which the valve will open and a thermostat 64a is mounted

in the header 42 as a guide in making the adjustment.

Each air and vapor discharge conduit 41 is provided with a cutoff valve 65 and a forwardly opening check valve 66. Any condensate resulting from the condensation of steam in the header 42 may be withdrawn through a steam trap 67 to the pumping trap 18, by which it will be returned to the boiler. Likewise any condensate accumulating in the steam supply header 7 may be withdrawn through a steam trap 68 to the pumping trap 18. Each condensate discharge conduit 16 is provided with a cutoff valve 69 and a forwardly opening check valve 70. Some air, flash steam or the like may pass into the condensate header 17 along with the condensate. That header preferably has a slight pitch so that the gaseous substances will accumulate at the higher end thereof and that end is vented to permit the escape of the gaseous substances, as by a pipe 71 connecting the higher end of the header 17 with the higher end of the header 42 and provided with a check valve 72 to prevent reverse flow of the vapors therethrough.

While I have shown and described one embodiment of my invention I wish it to be understood that I do not desire to be limited to the details thereof as various modifications may occur to a person skilled in the art.

Having now fully described my invention what I claim as new and desire to secure by Letters Patent is:

1. In an apparatus comprising a plurality of rotatable drums, means for connecting each drum with a source of steam supply, means connected with the respective drums at the axes thereof for withdrawing therefrom condensates and gaseous substances, normally open conduits for condensates connected with the respective withdrawing means and extending downwardly therefrom, a header below the axes of said drums connected with said conduits to receive said condensates, normally open conduits for gaseous substances connected with the respective withdrawing means and extending upwardly therefrom, a normally closed header above the axes of said drums connected with said upwardly extending conduits to receive gaseous substances therefrom, the last mentioned header being inclined to cause gaseous substances to flow toward the higher end thereof and having an outlet adjacent said higher end, and means controlled by the temperature in said last mentioned header to control the flow of gaseous substances through said outlet.

2. In an apparatus comprising a plurality of rotatable drums, means for connecting each drum with a source of steam supply, means connected with the respective drums at the axes thereof for withdrawing therefrom condensates and gaseous substances, normally open conduits for the gaseous substances connected with the respective withdrawing means and extending upwardly therefrom, a normally closed header above the axes of said drums connected with said upwardly extending conduits to receive gaseous substances therefrom, means for discharging said gaseous substances from said header, normally open conduits for condensates connected with the respective withdrawing means and extending downwardly therefrom, a header below said axes connected with said downwardly extending conduits to receive said condensates therefrom, the lower header being connected at one end with a trap, having its other end closed and so arranged

that gaseous substances entering the same with said condensates will move to the closed end thereof, and means for conducting said gaseous substances from said lower header to the upper header.

3. In an apparatus comprising a plurality of rotatable drums, means for connecting each drum with a source of steam supply, means connected with the respective drums at the axes thereof for withdrawing therefrom condensates and gaseous substances, normally open conduits for condensates connected with the respective withdrawing means and extending downwardly therefrom, a header below the axes of said drums connected with said conduits to receive said condensates therefrom, normally open conduits for gaseous substances connected with the respective withdrawing means and extending upwardly therefrom, a normally closed header above the axes of said drums connected with said upwardly extending conduits to receive gaseous substances therefrom, said headers being inclined to cause gaseous substances to flow to the higher ends thereof, means for connecting the higher ends of

5 said headers to cause gaseous substances to flow from said lower header to said higher header, a trap connected with the lower end of said lower header, and means for connecting the lower end

5 of said upper header with said trap to conduct condensates from the upper header to said trap.
